UNITED STATES PATENT OFFICE.

ARTHUR MASTERS PEACOCK, OF WIGAN, ENGLAND.

VANITY CASE OR POWDER BOX.

1,416,503.

Specification of Letters Patent. Patented May 16, 1922.

Application filed July 12, 1921. Serial No. 485,737.

To all whom it may concern:

Be it known that I, ARTHUR MASTERS PEACOCK, residing at Wigan, Lancashire, England, a subject of the King of Great Britain, 5 have invented certain new and useful Vanity Cases or Powder Boxes, of which the following is a specification.

This invention relates to vanity cases or powder boxes and its object is to provide 10 improvements therein.

The invention consists in a vanity case or powder box having an opening therein with inward projections, and a lid adapted to fit in said opening and be retained therein by 15 said projections. The case or box may be equipped with a puff, a sifter screen and with a scraper for removing excess powder from the puff.

According to one constructional form of 20 the invention, two oppositely disposed projections are provided on the box and the lid is hinged or made foldable across its centre so that, when folded, it can be inserted in the opening in the box and then be retained 25 therein by turning it until the hinge lies beneath the projections.

In a modification the lid, instead of being foldable, has openings in its periphery corresponding to the projections on the box so 30 that when the opening and projections are brought to register the lid can be inserted in, or removed from, the box, but not otherwise.

The invention will now be described with reference to the accompanying drawings 35 whereon:—

Fig. 1 is an isometric view of a powder box and lid in accordance with the invention.

Fig. 2 is a corresponding view to Fig. 1 showing the manner of removing the lid 40 from the box.

Fig. 3 is another view showing the box without the lid.

Fig. 4 is a cross sectional view of the box to show the construction.

Fig. 5 shows the powder box with another 45 form of lid in which the hinge is dispensed with and the removal of the lid obtained by providing openings therein corresponding to the projections in the box.

Referring to the drawings:—

The box and lid shown at Figs. 1 to 4 are made as follows:—

The box 1 has a circular opening and a circular lid 2 which is hinged at 3 and has 55 a puff 2^a at its under side. At the sides of the opening in the box I provide projections

4. The opening in the box is made slightly larger than the lid 2 so that the latter can fit into the opening in the box and rest on a circular flange 5 retained in position by a washer or distance piece 5^a. Below the flange 5 I provide another circular flange 6. A suitable distance piece 7 is provided between the flanges 5 and 6 and a suitable distance piece 8 is provided between the flange 6 and the bottom 9 of the box. To the under side of the flange 6 I secure gauze or equivalent filter material 10 which forms a sifter screen for the powder in known manner. In addition to, or in lieu of this screen 10 I may 70 provide a wire, or equivalent, 11 across the box as shown by the dotted lines at Fig. 4. This wire or equivalent forms a scraper such that when the lid 2 is turned under the projections 4, the powder puff 2^a will be 75 drawn across the same and will have any excess of powder removed before the lid is taken from the box.

In the example shown at Figs. 1 to 4 the lid 2 is removed by turning it round until 80 the hinge 3 is clear of the projections 4 and by pulling it upwards and at the same time slightly depressing the portions of the lid on each side of the hinge with the tip of the thumb and finger as shown at Fig. 2. The 85 lid can be placed in position again by slightly depressing said portions so that the edge of the lid can be inserted under the projections 4 and then, by turning the lid until the hinge 2 is below the projections 4 the lid 90 will be held securely in position.

At Fig. 5 a powder box and lid are shown in which, instead of the hinge, openings 12 are provided in the lid and such that when the lid is placed with the projections 4 in 95 register with the openings 12, the lid 2 can be removed from, or placed in position in, the box. The lid 2 is retained in the box by turning the edge of the lid under the projections 4 so that the openings 12 are not in 100 register with said projections.

Having now fully described my invention what I claim and desire to secure by Letters Patent is:—

1. A powder box having a circular opening with two diametrically opposite projections, a lid foldable across its centre adapted to fit in said opening, and a puff attached to the underside of the lid. 105

2. A powder box having a circular opening with two diametrically opposed projections, a lid foldable across its centre adapted 110

to fit in said opening and a filter within the box.

3. A powder box having a circular opening with two diametrically opposed projections, a lid foldable across its centre adapted to fit in said opening, a filter within the box, and means for retaining the filter in position between the bottom and the top thereof.

4. A powder box having a circular opening with two diametrically opposed projections, a lid folded across its centre adapted to fit in said opening, a puff carried by the lid, a filter and a scraper within the box, means for retaining said filter and said 15 scraper one above the other therein, and a seat for the lid within the box.

5. A powder box having an opening with inward projections, a lid adapted to fit in said opening and be retained therein by said 20 projections, a puff carried by the lid and a scraper for the puff within the box.

6. A powder box having a circular opening with two diametrically opposed projections, a lid hinged across its centre adapted to fit in said opening and be retained therein 25 by turning it until the hinge is beneath said projections, a puff carried by said lid, and means for removing surplus powder from the puff as it is turned round in the box.

7. A powder box having an opening with 30 inward projections, a lid adapted to fit in said opening and be retained therein by said projections, a grip on one side and a puff on the other side of the lid, a sifter within the box and means for retaining said sifter in 35 position therein.

In testimony whereof I affix my signature in presence of two witnesses.

ARTHUR MASTERS PEACOCK.
